FIG. 1

FIG. 2

INVENTOR
Benjamin L. Homel
BY M. R. Deline
ATTORNEY

UNITED STATES PATENT OFFICE.

BENJAMIN L. HOMEL, OF LUDINGTON, MICHIGAN.

DESIGN FOR A SHIRT.

59,959.

Specification for Design.

Patented Dec. 13, 1921.

Application filed October 17, 1921. Serial No. 508,379. Term of patent 14 years.

To all whom it may concern:

Be it known that I, BENJAMIN L. HOMEL, citizen of the United States, residing at Ludington, in the county of Mason and State of Michigan, have invented a new, original, and ornamental Design for Shirts, of which the following is a specification, reference being had to the accompanying drawing, forming a part thereof.

Figure 1 is a perspective view showing the front of a shirt made in accordance with my design, and

Fig. 2 is a perspective view showing the rear thereof.

I claim:

The ornamental design for a shirt as shown.

BENJAMIN L. HOMEL.
